UNITED STATES PATENT OFFICE

OTIS W. GALLOWAY, OF MINNEAPOLIS, MINNESOTA

BOX CAR CONSTRUCTION

Application filed October 27, 1930. Serial No. 491,352.

This invention relates to freight car construction and particularly to a reinforcing and protective door post construction for box cars. My structure may be applied to 5 wooden, all metal or combined wood and metal cars.

At the present time in shipping grain, vegetables or other food products, as well 10 as in the shipment of merchandise, the articles of which are of smaller dimensions than the width of the doorways, slats or inner doors are fastened, usually by nails, to the inner edges of the door posts and siding of the cars. The continuous nailing and extraction of nails in the door post and siding 15 considerably weakens the structure of the box car and occasions frequent replacement of the posts and the entire siding, thereby causing the railroad companies considerable 20 expense.

It is an object of my invention to provide a simple, efficient and indestructible door 25 post structure for box cars which will eliminate the above stated objectionable features of structures extensively utilized at this time and which will materially reinforce and 30 strengthen the construction of the car, as well as provide efficient protection to the ends of the siding members adjacent the doorways.

It is a further object to provide rugged 35 door post structure of the type above described having associated therewith removable wooden fillers or nailing blocks to which the grain doors, slats or lumber constituting the inner door of the car, may be secured without injury to the door posts and siding, 40 said structure including means for covering and protecting the outermost corners or edges of the filler members.

Still a further object is the provision of 45 door post structure of the type described having conveniently associated therewith efficient weather sealing elements for cooperating with the vertical edges of the box car doors.

These and other objects of the invention 50 will be more apparent from the following description made in connection with the accompanying drawing, wherein like reference

characters refer to similar parts throughout the several views, and wherein,

Fig. 1 is a fragmentary elevation taken from the interior of a wooden box car having my improved structure embodied therein; 55

Fig. 2 is a cross section taken on the line 2-2 of Fig. 1; and

Fig. 3 is a vertical section taken on the line 3-3 of Fig. 1.

In the drawing, a portion of one of the side 60 walls of a wooden box car is illustrated, including the doorway and my improved door post structure. The box car body includes the usual heavy lintel and sill 4 and 5 respectively, the flooring 6 secured to the lower sills 65 and the usual siding 7 constituting the walls of the box car. My door post structure includes heavy vertical door posts 8 and 9 respectively, which are preferably constructed 70 of metal and which are interposed between and secured to the lintel 4 and sill 5. The ends of said post members 8 and 9 may be conveniently and rigidly secured to members 4 and 5 by means of angle brackets 10, or if 75 desired the ends of the posts may be out-turned to form attachment feet which may be bolted, screwed or otherwise secured to the sills. The door posts 8 and 9 are generally 80 similar in construction comprising heavy Z bars having relatively wide flanges 8b and 9b respectively which are turned at right angles 85 to the intermediate sections or webs 8a and 9a and which overlap the inner surfaces of the wall siding 7 on the interior of the car and are rigidly secured thereto by suitable 90 means such as the bolts 11. The Z-bar posts 8 and 9 have the relatively narrow flanges 8c and 9c respectively which extend at right angles from the webs 8a and 9a and are disposed at the exterior of the doorway.

Removable, vertical filler members 12 are bolted or otherwise secured by bolts 12a to the intermediate portions or webs of the door posts 8 and 9 and are preferably of similar width to the said webs of the posts. These fillers may extend the full height of posts 8 and 9 or if desired, from the floor to points below lintel 4. Heavy boards, such as "two by sixes" may conveniently be utilized for 95 the removable filler members and it will be 100

noticed that the outer edges of said filler members 12 will be reinforced and protected by the narrow flanges 8c and 9c of the posts, while the inner edges of the fillers are exposed.

Both the posts 8 and 9 are provided with inturned flanges 13a and 14a respectively which may be constructed integrally with the said Z-bars or which, as shown, may constitute integral portions of weather sealing elements welded or otherwise rigidly connected to the outer faces of the flanges 8c and 9c. In-turned flanges 13a and 14a overlie the inner and opposing faces of filler members 12 and protect the vertical edges or corners of the same.

My weather sealing elements referred to are numbered 13 and 14 respectively. Element 13 is secured to the front door post 8 and extends vertically along the outer face of the post having a projecting weather sealing portion or channel 13b of U-shape cross section adapted to surround and engage the forward edge of the sliding car door D. Weather sealing element 14 comprises a vertical strip carrying the previously mentioned protective flange 14a and secured to the outer face of the rear door post 9 and having a weather sealing flange or edge 14b which is offset somewhat outwardly from the attachment portion of the strip. Said flange 14b is engaged and surrounded by a sealing element or channel 15 secured to the rear edge of door D and extending vertically thereof.

As shown in Figures 2 and 3, the door D is of a conventional sliding type used on box cars, supported by a pair of hangers 16 from a track 17 which may be rigidly secured to the outer surface of the lintel 4. Hangers 16 are equipped with the usual rollers 16a which travel over the horizontal portion of said track. A guide in the form of an angle bar 18 engages the lower edges of the door D.

The heavy metallic door posts 8 and 9 additionally strengthened because of their cross sectional Z-shape, materially strengthen the box car construction supporting the lintels 4 and rigidly connecting said upper sills with the lower sills 5. It will further be noticed that the wide inner flanges 8b of the door posts reinforce the inner ends of the siding members 7 and cover completely the innermost surfaces of said ends for a considerable area. It will thus be impossible to nail slats or grain doors across the ends of the siding. The replaceable filler strips or nailing blocks 12 fit the intermediate portions or webs of the Z-bar posts 8 and 9 with their innermost edges disposed substantially flush with the inner faces of the siding and the protective flanges 8b and 9b, furnishing adequate attachment means to which the grain doors or slats may be nailed or otherwise secured.

In loading box cars, the outermost edges of the doorway are frequently struck and in-

jured by heavy articles. With my structure, said edges and corners of the filler members 12 are completely protected by the outermost flanges of the door post and by the protective inturned flanges 13a and 14a.

70

Elements 13 and 14 cooperate to provide efficient weather sealing structure for the car door D, channel element 14b sealing the forward vertical edge of the door while the vertical channel 15 carried by the rear edge of door D engages the offset flange 14b of element 14.

75

It will be noticed that the filler strips 12 may be quickly removed from the door posts 8 and 9, the bolts or other securing means being accessible in the form illustrated, from the exterior of the box car.

80

It will, of course, be understood that various changes may be made in the form, details, arrangement and proportions of the various parts without departing from the scope of my invention.

85

What is claimed is:—

1. In combination with the lintel and sill and siding of a box car, door post construction comprising a pair of metallic posts interposed between said lintel and sill and rigidly secured thereto and cooperating therewith to define a doorway, said posts being of approximately Z-shape in cross section and having relatively wide protective flanges at their inner surfaces, said flanges overlying and protecting the inner surfaces of the ends of the siding members adjacent the doorway, means for rigidly securing said siding ends to said flanges, removable filler members extending longitudinally of said post and secured to the web portions of said Z-bars, said posts having inturned protective flanges covering the outermost edges of said filler members.

90

2. In combination with the lintel and sill and siding of a box car, door post construction comprising a pair of metallic posts the ends of which are rigidly connected respectively with said lintel and sill, removable filler members extending longitudinally of said posts and secured to the inner and opposed surfaces thereof, said posts having at the exterior of the box car opposed longitudinal angle flanges forming in conjunction with the opposed longitudinal surfaces of said posts longitudinal channels which surround and protect the forward edges and corners of said filler members.

95

3. In door post structure for box cars, a pair of vertical metallic posts secured at their upper and lower ends to the lintel and sill respectively of the box car and cooperating with said lintel and sill to define a doorway, said posts having opposed substantially parallel intermediate longitudinal portions or webs and having outwardly turned perpendicular and relatively wide flanges at their rearward portions which lap and protect the inner surfaces of the ends of the siding mem-

bers of the box car, means for securing said wide flanges to the ends of said siding members, said metallic posts having inturned substantially perpendicular and relatively narrow longitudinal flanges at their forward portions, said last mentioned flanges cooperating with the intermediate or web portions of the posts to define longitudinal seats for removable filler strips and opposed filler strips

10 detachably secured in said seats.

4. In door post structure for box cars, a pair of vertical metallic posts secured at their upper and lower ends to the lintel and sill members respectively of a box car and cooperating therewith to define a doorway, said posts having opposed substantially parallel longitudinal webs, vertical filler strips detachably secured against said webs, said posts having outwardly turned perpendicular and relatively wide flanges at their rearward portions extending substantially throughout the full length of said posts and overlapping flush against the inner surfaces of the ends of the siding members of the box car to protect the same and means for securing said wide flanges to said siding.

In testimony whereof I affix my signature.
OTIS W. GALLOWAY.
